(57) CLAIM

The ornamental design for a trouser attachment, as shown and described.

DESCRIPTION

FIG. 1 is a perspective view of a trouser attachment;
FIG. 2 is a front view of the trouser attachment;
FIG. 3 is a rear view of the trouser attachment;
FIG. 4 is a right side view of the trouser attachment;
FIG. 5 is a left side view of the trouser attachment; and,
FIG. 6 is a top plan view of the trouser attachment.
The shade lines in the Figures show contour and not surface ornamentation.
